FIREPLACE OR SIMILAR ARTICLE

Ray Derringer, Port Edwards, and Thomas F. Billmeyer,
Wisconsin Rapids, Wis., assignors to Preway Inc.

Filed Dec. 29, 1971, Ser. No. 213,777

Term of patent 14 years

Int. Cl. D23—03

U.S. Cl. D23—94

Fig. 1.

Fig. 2.

Fig. 3.

FIG. 1 is a perspective view of the front and one side of the fireplace or similar article showing our new design;

FIG. 2 is a side elevational view looking toward the right of FIG. 1; and

FIG. 3 is a top plan view of FIG. 1.

The mesh in FIG. 1 is partially shown for convenience of illustration, it being understood that the mesh is continuous over the area indicated.

We claim:

The ornamental design for a fireplace or similar article, substantially as shown and described.
